US00D616740S

(12) **United States Design Patent**
Akers et al.

(10) **Patent No.:** US D616,740 S
(45) **Date of Patent:** ** *Jun. 1, 2010

(54) **CONTAINER**

(75) Inventors: **Brian Ray Akers**, Cincinnati, OH (US);
Christine Ann Kron, Liberty Township,
OH (US)

(73) Assignee: **The Procter & Gamble Company**,
Cincinnati, OH (US)

(**) Term: **14 Years**

(21) Appl. No.: **29/286,347**

(22) Filed: **May 2, 2007**

(51) **LOC (9) Cl.** **09-03**

(52) **U.S. Cl.** **D9/432**

(58) **Field of Classification Search** D9/430-433,

CLAIM

The ornamental design for a container, as shown and described.

DESCRIPTION

FIG. 1 is a perspective view of a first embodiment of a container;

FIG. 2 is top view of the container of FIG. 1;

FIG. 3 is a front view of the container of FIG. 1;

FIG. 4 is a right side view of the container of FIG. 1;

FIG. 5 is a left side view of the container of FIG. 1;

FIG. 6 is a rear view of the container of FIG. 1;

FIG. 7 is a bottom view of the container of FIG. 1;

FIG. 8 is a perspective view of a second embodiment of a container;

FIG. 9 is top view of the container of FIG. 8;

FIG. 10 is a front view of the container of FIG. 8;

FIG. 11 is a right side view of the container of FIG. 8;

FIG. 12 is a left side view of the container of FIG. 8;

FIG. 13 is a rear view of the container of FIG. 8; and,

FIG. 14 is a bottom view of the container of FIG. 8.

The broken lines represent unclaimed environmental subject matter.
